BARBECUE UNIT

Robert L. Rodman, Alliance, Ohio

Application January 28, 1957, Serial No. 44,621

Term of patent 14 years

(Cl. D81—10)

FIG. 1

FIG. 3

FIG. 2

Fig. 1 is a view in perspective from the rear and at one side of the barbecue unit showing my new design with the hood open and with the handle which controls the height of the grill in the raised position;

Fig. 2 is a rear perspective view similar to that shown in Fig. 1, but with the hood in closed position, the handle lowered, and with portions of the wheels broken away for convenience of illustration; and

Fig. 3 is a side view of the barbecue unit with the hood open and the handle raised.

The characteristic features of my design reside in the portions shown by means of full lines in the drawing.

I claim:

The ornamental design for a barbecue unit, as shown and described.
